FIG. 1 is a top, front, perspective view of a debris capturing net showing my new design;
FIG. 2 is a top plan view thereof;
FIG. 3 is a bottom plan view thereof;
FIG. 4 is a rear elevational view thereof;
FIG. 5 is a front elevational view thereof; and,
FIG. 6 is a left side elevational view thereof, the right side elevational view being a mirror image thereof.
The dashed lines shown in FIG. 1 are included for the purpose of illustrating environment and form no part of the claimed design.
